United States Patent Office

Des. 181,532
Patented Nov. 26, 1957

181,532

FAUCET

Julius Hurwitz, Floral Park, N. Y.

Application June 13, 1957, Serial No. 46,581

Term of patent 3½ years

(Cl. D91—3)

Fig. 1.

Fig. 2.

Fig. 3.

Fig. 1 is a side elevational view of a faucet, showing my new design;

Fig. 2 is a top plan view thereof; and

Fig. 3 is a front elevational view of Fig. 1.

I claim:

The ornamental design for a faucet, as shown.
